UNITED STATES PATENT OFFICE

WILLIAM J. HIGMAN, OF DENVER, COLORADO

METAL OR COMPOSITION COLLAPSIBLE FIREPROOF AWNING

Application filed April 20, 1931. Serial No. 531,511.

My invention relates to improvements in metal or composition collapsible fire-proof awnings.

The main object of the invention is to provide an awning made of a composition or of thin sheet metal or any other suitable material and which comprises a number of swinging sections arranged one within another, each section, when in open position being supported by the section immediately above it, and the uppermost section being supported by a permanent housing or frame which is secured to the frame of the window, each section being adapted to engage and lift the section above it, when the awning is being closed or collapsed so that the sections are successively swung upward, one within another, until all of the sections enter the permanent housing frame, operating cords being secured to the innermost section, which pass over suitable pulleys and terminate in a hand cord.

Further, to provide a plurality of awning sections arranged one within another, each comprising opposite side members connected at their outer ends by a flat plate or strip, each set of side members being pivotally supported at their inner ends, the rear edge of each plate being upwardly curved into hook shape and the forward edge being rolled outwardly and provided with inwardly turned hooks, whereby, in opening, the inner hooked edge of one plate engages the hooks on the outer edge of the overlying plate, and in closing the rolled edge of one plate engages the hooks on the overlying plate, so that each section acts to lift the next overlapping section.

Further, to provide an awning which not only lasts for a much longer period than the canvas awnings in present use, but which may be painted from time to time so as to present a pleasing appearance.

These objects are accomplished by the char-

acter of awning illustrated in the accompanying drawings, in which:—

Fig. 1 is a front view of the improved awning as it appears when open and secured within a window frame. 50

Fig. 2 is a sectional view of Figure 1.

Fig. 3 is a side view, partly in section, of the awning as it appears when closed or collapsed, and detached from a window frame.

Fig. 4 is a vertical sectional view through 55 a portion of one of the awning sections.

Fig. 5 is a perspective view of a portion of one of the awning sections.

Fig. 6 is a transverse sectional view through the inner or hinge end of one of the side members of an awning section, and 60

Fig. 7 is an enlarged sectional view showing portions of two sections, in hooked engagement and showing a slight modification in the hook. 65

Referring to the accompanying drawings:—

The numeral 1 designates a window frame, and 2 and 3 the upper and lower sashes respectively. The letter A refers to the improved awning and B to a frame which incloses the folded or collapsed awning, and which also limits the outward movement of the outermost section of the awning in a manner to be presently described. 75

The frame B comprises a pair of side members 4, which are connected at their upper ends by a cross plate 5. The cross plate 5 is secured to a cross bar 6 of the window frame and inclines downwardly and outwardly at 80 an angle of about forty-five degrees, and the side members 4 taper from the cross plate to their lower ends, which are supported on pins or bolts 7 which pass through U-brackets 8, having threaded stems 9, which are secured 85 to angle brackets 10, which are secured to the side members of the window frame, as clearly shown in Figures 1 and 2.

The lower edge of the cross plate 5 is rolled, as shown at 11, to stiffen it and is further 90

strengthened by a tube 12, which is inserted in the roll. Upon the under side of the rolled edge portion of the cross plate are secured two or more short metal strips 13, the outer ends 5 of which are inwardly bent to form hooks 14, the purpose of which will later appear.

The awning is made up of a plurality of yoke-shaped sections which are arranged one within another, six of such sections being 10 shown in the drawings, and beginning with the innermost or shortest and narrowest section are numbered, respectively 15, 16, 17, 18, 19 and 20. Each section comprises side strips 21, which are connected at their outer ends by 15 cross plates 22, the widths of which are each approximately one-sixth of the arc of the awning. The side strips 21 taper toward their inner ends which are pivotally supported on the pins 7 of the U-brackets 8 previously 20 referred to. These side strips are stiffened by folding over their edges, and additional stiffness and thickness is given their lower end portions, by short reinforcing strips 23, which are held in place by the folded edges 25 of the side strips, as clearly shown in Figures 2, 4 and 6. The forward edge of each cross plate 22 is upwardly rolled, as shown at 24, to stiffen it and tubes 25 are inserted in the rolls, which further stiffen them and thus prevent 30 bending or sagging of these edges, particularly in the case of very wide awnings. The opposite edges of the cross plates are bent or rolled into hook shape as shown at 35 26 and two or more narrow strips 27 are secured to the inner side of each cross plate and the rear ends of these strips are bent around the hooked edges 26, so as to reinforce them while their forward ends are bent to 40 form hooks 28, which lie back of the rolled edges 24. In Figure 1 of the drawings, each cross plate is provided with three of the hooked strips 27, one near each end and one in the center, but a greater number may be 45 employed in the case of wide awnings, if desired. When the awning is open, as shown in Figures 1 and 2, the sections are supported in the following manner:

The hooked edge 26 of the outer section 20, 50 engages the hooks 14 on the lower edge of the cross plate 5 of the frame B; the hooked edge 26, of the section 19, engages the hooks 28, on the section 20; the hooked edge 26 of the section 18 engages the hook 28 on the section 19, and so on, in this manner to the last section 15.

The side members of each section, beginning with the section 20, slightly overlap the side members of the next succeeding section, 60 so as to leave no open spaces between the sections, and washers 29 are placed between the pivoted ends of the said side members, to prevent frictional contact of one member with another. Eyelets 30 are secured to the cross plate of the inside section 15 and cords 31 are

secured to these eyelets and are passed up over pulleys 32 which have a swinging connection with the side members of the window frame, near the upper ends of said members, and from the pulleys, the cords pass respectively over pulleys 33, which are secured to the central portion of the cross bar 6 of the window frame, after which, they unite in a single cord 31A, which extends down far enough to be conveniently grasped, and a cleat 34 is secured to the window sill over which the cord 31A may be wound to hold the awning in a closed position.

In narrow windows, the pulleys 33 may be dispensed with, and the cords 31 may extend directly down from the pulleys on the sides of the window frame and may be secured to cleats at the lower ends of said frame. Any other arrangement of the cords and pulleys, however, may be employed. Cords 35 are 85 also secured to the eyelets 30, and when the awnings are open, these cords are secured at their opposite ends to cleats 36 on the window frame, thereby preventing either rattling or upward movement of the sections, due to 90 wind.

When the cord 31A is drawn upon to close the awning, the lower section 15 is swung up until its rolled edge 24 engages the hook 28 on the next succeeding section 16, and the two sections 15 and 16 are then lifted simultaneously until the rolled edge 24 on the section 16 engages the hooks 28 on the next section 17, and so on in this manner, each section lifting the section above it, until all of the sections are swung back into the frame B, as shown in Figure 3, and the cord 31A is wound upon the cleat 34, to secure the awning in closed or collapsed position.

The cross plate of the frame B as well as those of the sections 18, 19 and 20, are preferably made of thicker material than those of the other sections, in order to withstand the direct pounding force of large hail stones. The cross plate 5 of the frame B is provided with vent openings 37, which are formed by cutting tongues 38 in the plate, and bending the tongues up in the manner shown most clearly in Figure 2. The side plate 21 of the several sections are also provided with a plurality of vent holes 39. A space is left between the engaging edges of each two cross plates, as will be most clearly understood by reference to Figure 7, and these spaces permit the passage of wind and thus relieve the cross plates of the wind pressure, and the vent openings 37 and 39 will permit the escape of wind from beneath the awning. They also cause an air circulation under and through the awning, thus continuously carrying off 125 hot air from beneath the awning.

In Figure 7, I show two short hooked strips 27A and 27B instead of the single strip 27, as in the other views, but they serve the same purpose.

The improved awning overcomes many of the objectionable features of the canvas awnings in present use, in that it is not subject to injury from sudden wind storms or from the 5 careless throwing of lighted matches or cigar ends from windows above it, and also because it can be painted when desired so as always to present a neat and attractive appearance.

Having described my invention what I 10 claim as new and desire to secure by Letters Patent is:—

1. An awning of the character described, comprising a plurality of sheet metal sections fitting one within another each comprising 15 side members adapted to be pivotally supported at their inner ends, and provided with ventilating apertures adjacent their outer ends, their outer ends being connected by cross plates, the rear edges of said plates 20 being bent to form outward abutments, and their forward edges having inward abutments and outwardly rolled edges, a yoke shaped supporting frame surrounding said sections and having a stop to engage the outward 25 abutment on the outermost section to limit its forward swinging movement and ventilating apertures in its cross member, the forward movement of each succeeding section being limited by the engagement of its 30 outward abutment with the inward abutment of the preceding section, the rolled edge of each section engaging the inward abutment of the next succeeding section when the innermost section is swung in a reverse direction, 35 to a vertical position, whereby each section is swung into the next succeeding section.

2. An awning comprising a plurality of telescoping sections, each comprising side members adapted to be pivoted at their inner 40 ends, their outer ends being connected by cross plates, the rear edges of which are upwardly and outwardly curved into hook form, while their forward edges are upwardly rolled, and inwardly turned hook members 45 on the under side of said forward edges, said side members being reinforced at their inner end portions.

3. An awning comprising a plurality of telescoping sections, each comprising a yoke 50 shaped member, the edges of the side members of which are folded to stiffen said members, reinforcing strips on the inner end portions of said side members, which are clamped by said folded edges, the rear edge of the 55 cross member of said section being outwardly bent into hook shape, its forward edge being outwardly rolled, and inwardly bent hook members secured to said cross member back of said rolled edge, the outer portions of said 60 side members being provided with a plurality of ventilating apertures.

In testimony whereof, I affix my signature.
WILLIAM J. HIGMAN.
